PLAQUE

Darrell M. Johnson, 121 E. Hill St.,
Thomson, Ga. 30824

Filed Jan. 9, 1973, Ser. No. 322,256

Term of patent 14 years

Int. Cl. D11—02

U.S. Cl. D29—23 A

FIG. 1

FIG. 2

FIG. 3

FIG. 4

FIG. 1 is a front elevational view of a plaque, showing my new design;

FIG. 2 is a bottom edge view thereof;

FIG. 3 is a rear elevational view on a slightly reduced scale; and

FIG. 4 is a vertical edge elevational view on the same scale as FIG. 3.

I claim:

The ornamental design for a plaque, as shown.
